(No Model.)

A. H. MARDEN

CAR BRAKE.

No. 374,798.

Patented Dec. 13, 1887.

UNITED STATES PATENT OFFICE.

ALDIS H. MARDEN, OF WALTHAM, MASSACHUSETTS.

CAR-BRAKE.

SPECIFICATION forming part of Letters Patent No. 374,798, dated December 13, 1887.

Application filed July 9, 1887. Serial No. 243,813. (No model.)

To all whom it may concern:

Be it known that I, ALDIS H. MARDEN, of Waltham, in the county of Middlesex, State of Massachusetts, have invented a certain new and useful Improvement in Car-Brakes, of which the following is a description sufficiently full, clear, and exact to enable any person skilled in the art or science to which said invention appertains to make and use the same, reference being had to the accompanying drawings, forming part of this specification, in which--

Figure 1 is an enlarged side elevation, one brake-head and a portion only of the beam being shown; Fig. 2, an enlarged end elevation, the beam and link being shown in vertical section; Fig. 3, an enlarged side elevation of the clamp, represented as attached to the beam, the latter being shown in vertical section; Fig. 4, an enlarged side elevation of the members of the clamp detached; Fig. 5, an enlarged end view of the members of the clamp detached; Fig. 6, a top plan view of the beam, brake-heads, and clamp connected; and Fig. 7, a perspective view showing one of the notches in the end of the beam.

Like letters and figures of reference indicate corresponding parts in the drawings.

My invention relates more especially to the beam of the brake and its immediately-connected parts; and it consists in a novel construction and arrangement of parts, as herein-after more fully set forth and claimed, the object being to produce a stronger and more durable and effective device of this character than is now in ordinary use.

The nature and operation of the improvement will be readily understood by all conversant with such matters from the following explanation:

In the drawing, A represents the beam, B the brake-heads, and C the lever-clamp.

The heads are designed to be respectively suspended from the truck by links D, and are provided with shoes and otherwise constructed in the ordinary manner; excepting as herein-after set forth.

The beam A is composed of iron or steel rolled or pressed into shape, and consists of a flat web or body, m, having a double flange or T-shaped edge, f, at one side and a rib, x, at the opposite side, and is so arranged when in position for use that the web m will be in a horizontal or nearly horizontal position, or so

that its flange f will stand nearly at right angles to the line of strain, as best seen in Fig. 2.

The brake-heads B B are mortised or provided with openings to receive the ends of the beam, the mortises being so formed and arranged as to leave a portion of the web m and the rib x projecting from the heads, as shown in Figs. 1 and 2.

The beam is secured in the heads in the following manner: A notch, r, corresponding in width with the thickness of the brake-head at that point where the beam is inserted, is cut in the lower edge of the flange f, and the vertical part of the mortise which receives the flange f of the beam is made slightly longer or higher than the height of said flange, so that when the beam is inserted a portion of the brake-head will enter the notch r as the beam drops into position in the head. A key, v, is then driven into the mortise in the head above the flange f, and its point bent down, as shown at t, thereby securely locking the beam and head together in a manner which will be readily obvious without a more explicit description.

It will of course be understood that each end of the beam is provided with a notch, r, and that each of the heads is secured to the beam substantially as described.

The notches r may be formed in the upper edge of the flange f, if preferred, in which case the keys v will of course be inserted below the flange instead of above it.

The beam A is curved outward in the line or direction of the strain, as shown in Fig. 6, the curve preferably terminating at x near each end of the beam, in order that the heads, when attached to the beam, may stand in proper position with respect to the wheels of the truck.

The beam may be constructed straight instead of curved, if desired; but I deem a curved one preferable, as it is much stronger and less liable to bend or spring under a heavy strain.

The lever-clamp C is secured to the center of the beam by the bolts and nuts l h, as best seen in Figs. 1, 3, and 6.

The clamp is composed of two members or halves, g k, each of which is provided at its rear end with a flange, i, and at its front end with an arm, b, said flanges being provided with holes for receiving the bolt l and said arms with holes w, for receiving the bolt h. The

arms *b* respectively project horizontally from the bodies of the members *g* *k* and are arranged diagonally thereon and in parallelism with each other to properly receive the brake-lever, 5 (not shown,) which is inserted between them and pivoted therein by a bolt, (not shown,) which passes through the holes *y* near their outer ends.

The member *k* of the clamp is provided with 10 a shoulder or rabbet, 14, against which the lower corner, 15, of the body of the member *g* rests when the members are joined and in position on the beam, and the member *g* is provided with a shoulder or rabbet, 16, against 15 which the upper corner, 17, of the body of the member *k* rests when the members are joined and in position on the beam, these shoulders being very essential to prevent said members from swinging independently on the bolt *l* and 20 becoming loose. The member *k* is provided with a deep transverse groove, *j*, for receiving the lower edge of the flange *f*, and the member *g* with a corresponding groove, *j*, for receiving the upper edge of said flange. The 25 member *k* is also provided with a short outwardly-projecting lip or flange, 24, on which the lower portion of the inner end of the arm *b* on the member *g* rests when the members are joined, the member *g* being provided with 30 a corresponding outwardly-projecting lip or flange, 25, which rests on the upper portion of the inner end of the arm *b* on the member *k* when the members are joined and in position on the beam, said lips or flanges acting as 35 braces to strengthen the arms and keep them steady.

In attaching the clamp to the beam a hole is drilled centrally in the web *m* for the reception of the bolt *l*, and the members *g* *k*, 40 placed on the T-shaped portion of the beam with their front edges, 20 and 21, in contact, and secured by the bolts and nuts *l* *h*, as best seen in Fig. 3.

The object in making the clamp *C* in two 45 parts, as described, is to enable it to be readily attached to or detached from the beam *A* without the necessity of removing either of the heads *B* *B*, as would have to be done if all the members of the clamp were integral and the 50 clamp provided with a mortise or opening for receiving the T-shaped portion of the beam. The object of the rib *x* is to strengthen the beam and keep the web or body *m* from twisting or warping under a heavy strain. It is 55 preferably made round in cross section, but may be made of any other suitable shape.

I do not confine myself to securing the beam in the head by means of the notch *r* and key *v*, as it may be secured in any other suitable 60 manner; neither do I confine myself to the use of the sockets 14 and 16, as one or both may be omitted; nor the lips or flanges 24 and 25 in the members *k* *g*, as the same may be dispensed with, if desired, although I deem it 65 preferable to employ them; nor to attaching the clamp *C* to the beam by means of the bolts

and nuts *l* *h*, as it may be attached in any other suitable manner.

I do not herein claim, broadly, anything shown and described in Letters Patent of the 70 United States No. 270,962, dated January 23, 1883, my present invention being designed as an improvement on the brake secured to me by said Letters Patent.

Having thus explained my invention, what 75 I claim is—

1. In a car-brake of the character described and having a metallic beam connected with a brake-head at each end, a clamp for the brake-lever, said clamp comprising two separable 80 members and being adapted to be attached to or removed from the beam without removing either of said heads, substantially as described.

2. In a car-brake of the character described, 85 the combination of the following instrumentalities, to wit: a curved metallic beam, two brake-heads connected with said beam, a clamp for the brake-lever, and means for securing the clamp on the beam, said clamp comprising two separable members and being adapted to be attached to or removed from the beam without removing either of said heads, substantially as set forth.

3. The clamp *C*, composed of the members 90 *g* *k*, each of said members being provided with a flange, *i*, groove *j*, and diagonally-arranged arm *b*, each of said flanges being provided with a bolt-hole, and each of said arms with holes *w* *y*, substantially as described.

4. The member *k*, provided with the shoulder or socket 14 and corner 17, in combination with the member *g*, provided with the shoulder or socket 16 and corner 15, said corners being respectively adapted to rest in 105 said sockets when said members are joined, substantially as and for the purpose set forth.

5. The member *k*, provided with the flange 24, arm *b*, and flange *i*, in combination with the member *g*, provided with the flange 25, 110 arm *b*, and flange *i*, substantially as and for the purpose specified.

6. In a car-brake of the character described, the clamp *C*, composed of two members or halves, beam *A*, bolts and nuts *l* *h*, and heads 115 *B* *B*, combined and arranged substantially as described.

7. In a car-brake substantially such as described, the combination of a curved metallic beam consisting of a T-shaped bar provided 120 with a strengthening-rib on the edge opposite the double flange or cross, two brake-heads in which the beam is secured, a clamp for the brake-lever, and bolts and nuts for securing the clamp to the beam, said clamp comprising 125 two separable members and being adapted to be attached to and removed from the beam without removing either of the brake-heads, substantially as set forth.

Witnesses: ALDIS H. MARDEN.
